UNITED STATES PATENT OFFICE.

GEORGE W. PACKER, OF CHICAGO, ILLINOIS.

ANNEALING-FURNACE.

SPECIFICATION forming part of Letters Patent No. 664,173, dated December 18, 1900.

Application filed July 26, 1900. Serial No. 24,869. (No model.)

To all whom it may concern:

Be it known that I, GEORGE W. PACKER, a citizen of the United States, residing at Chicago, in the county of Cook and State of Illinois, have invented certain new and useful Improvements in Annealing-Furnaces; and I do hereby declare the following to be a full, clear, and exact description of the invention, such as will enable others skilled in the art to which it appertains to make and use the same.

My invention relates to an improvement in annealing-furnaces by means of which castings can be annealed and decarburized in a shorter time and with less expenditure of fuel than in those now in use; and it consists in the parts and combinations herein described and claimed.

Referring to the drawings forming a part of this specification, Figure 1 is a longitudinal vertical section of my improved furnace on line *xx* of Fig. 2, and Fig. 2 is a transverse section.

1, 2, 3, and 4 are the chambers or ovens of my improved furnace.

5 5 are cases containing the castings, packed in the usual manner with any suitable material.

6, 7, 8, and 9 are oil-burners.

10 10 are passages or flues connecting the upper and lower chambers.

11 11 are flues leading from the lower chambers to the stack.

12 12 are openings between the two upper chambers 1 and 2. 13 13 are similar openings between the two lower chambers 3 and 4. The openings 12 and 13 may be closed in any suitable manner, as by fire-bricks, when desired.

14 14 are the usual charging-doors for the several chambers.

40 In the operation of my furnace the chambers 1, 2, 3, and 4 are charged with the cases 5, containing the castings, and the burners 6 and 7 of the upper chambers are lighted. The amount of air admitted along with the oil through the burners 6 and 7 is so proportioned that the oil is not at once thoroughly atomized, and complete combustion does not take place in the upper chambers 1 and 2. The products of combustion, together with 45 the unconsumed portion of the fuel, escape through passages or flues 10 10 to the lower chambers 3 and 4, where the combustion is

completed, the necessary air being supplied through burners 8 and 9 or in any other obvious manner. The products of combustion 55 then pass from the lower chambers 3 and 4 through the flues 11 11 to the stack. If the openings 12 12 have been left open, the communication between the upper chambers 1 and 2 will tend to equalize the temperature 60 thereof. Similarly the openings 13 13 will act to equalize the temperature of the lower chambers 3 and 4.

To obtain the best results, it is necessary that the heat be supplied gradually to the 65 castings in the annealing-furnace. Otherwise the castings near the walls of the cases 5 will be injuriously heated before the castings nearer the middle of the cases have been raised to a sufficient temperature. This re- 70 sult is obtained in the upper chambers of my furnace by the incomplete combustion of the fuel therein, while the completion of the combustion in the lower chambers supplies heat gradually and evenly to these chambers and 75 also prevents the wasteful escape of any unconsumed fuel through the stack. The fuel is supplied to the burners 6 and 7 of the upper chambers until the castings in these chambers are raised to such temperature that 80 they are unable to absorb any more heat. This is conveniently determined by examining the interior of the furnace through a peephole or by removing a brick from the furnace-wall to permit such inspection. After the 85 castings in the upper chambers have been raised to such temperatures the fuel is shut off from the burners 6 and 7. It will be found that the lower chambers 3 and 4 have been raised to a temperature somewhat below that 90 of the upper chambers 1 and 2 by the fuel supplied through burners 6 and 7. The burners 8 and 9 in the lower chambers are now lighted and fuel supplied thereto until the castings in the lower chambers have been 95 raised to the desired temperature, the products of combustion from said burners 8 and 9 escaping directly to the stack by way of flues 11. When the castings in the lower chambers 3 and 4 have been raised to the re- 100 quired temperature, the burners 8 and 9 are shut off and the furnace left to cool slowly, after which the castings are moved.

In a large furnace of this construction I

have found it necessary to supply fuel to the burners in the upper chambers for only three days and then to the burners in the lower chambers for twenty-four hours longer.

5 While I have shown my furnace adapted to burn oil, it is obvious that any other fuel could be employed.

Having thus described my invention, what I claim is—

10 1. In an annealing-furnace, the combination of an upper heating-chamber, a lower heating-chamber, separate charging means for each chamber, independent means for supplying fuel and air to each of said chambers, 15 flues leading from the upper chamber to the lower chamber, and outlet-flues leading from said lower chamber.

20 2. In an annealing-furnace, an upper heating-chamber, a lower heating-chamber, independent means for supplying fuel and air to the upper part of each of said chambers, flues leading from the lower part of said upper

chamber to the upper part of said lower chamber, and outlet-flues in the lower part of said lower chamber.

25

3. In an annealing-furnace, an upper heating-chamber consisting of a series of ovens or chambers, passages between the adjacent ovens of said series, a lower heating-chamber consisting of a series of ovens or chambers 30 and provided with passages between the adjacent ovens of said series, independent means for supplying fuel and air to each of the said ovens, flues leading from each of said chambers of the upper series to one of said 35 chambers of said lower series, and escape-flues in each of said lower ovens.

In testimony whereof I affix my signature in presence of two witnesses.

GEORGE W. PACKER.
